EXPANSIBLE COLLAR

Lucious C. Myrick, Nogales, Ariz.

Application January 5, 1956, Serial No. 557,568

4 Claims. (Cl. 2—116)

This invention relates to improvements in the collars and neckbands of shirts.

One of the objects of the invention is to provide a collar for a so-called "collar-attached" shirt which will fit a wider range of neck sizes than a conventional shirt of this type. Another object is to provide a self-adjusting neckband which conforms automatically and comfortably to the neck of the wearer and neatly to a necktie, when one is worn. Another object is to provide a stretchable collar so constructed that it will not be distorted by the stretching action. Another object is to provide an improved stretchable neckband in which the stretch mechanism is completely concealed, no matter whether the collar is worn open or closed, or with or without a necktie.

It is old to provide collars with neckbands which have elastic sections permitting the collars to be stretched. One example is shown in the U. S. patent to Tucker No. 1,963,004, Figures 3 and 4. This type of structure has the disadvantage that the stretching of the neckband stretches the collar proper where it is joined to the neckband and causes the points of the collar to stand out from the shirt. Figure 5 of the same patent to Tucker shows another expedient in which the button is secured to the neckband by a band of elastic. Even this structure causes the points of the collar to stand out from the shirt when the neckband is stretched. Furthermore, when the collar of Figure 5 is stretched, the overlapping portions of the shirt, including the ends of the neckband, separate, resulting in an untidy appearance.

One of the objects of the present invention is to overcome the disadvantages of prior structures similar to that shown in the above-identified patent.

Other objects and advantages of my invention will become apparent from the following description and the appended drawings wherein:

Fig. 1 is a fragmentary front elevation of the upper portion of a shirt showing a collar and neckband made in accordance with my invention, a portion of the collar being broken away to show the structure more clearly;

Fig. 2 is a section taken along line 2—2 of Fig. 1;

Fig. 3 is a section taken along line 3—3 of Fig. 1; and

Fig. 4 is a fragmentary front elevation of the upper portion of a shirt showing another form of my invention.

Referring now to the drawings, wherein like characters designate the same or similar parts, Figs. 1, 2, and 3 show a preferred form of my invention comprising a collar attached to shirt 20. The collar comprises a tubular neckband 24 attached along its lower edge by stitching 25 to the shirt 20 adjacent the top edge 20a thereof, and a collar portion proper 21 attached to tubular neckband 24 by stitching along the upper edge of neckband 24. In Figs. 2 and 3 neckband 24 has been shown bowed out in order to show the structure more clearly, but normally it lies flat and is not noticeably thicker than a conventional neckband. Tubular neckband 24 extends around the collar and terminates in open ends 24c which are spaced apart at the front of the shirt, one on each side, although only one open end is shown in Fig. 1. A tab 22 is pro-

2

vided in each of the open front ends 24c, being stitched to the top edge 20a of the shirt as at 29 by stitching which extends outwardly from the tubular neckband. This stitching also preferably extends inwardly for a distance 5 within the tubular neckband as indicated by the section shown in Fig. 2. The lines of stitching 25 and 29 are spaced apart for a reason which will be explained below. The inner end of each tab 22 is spaced inwardly from its corresponding open front end 24c and to this inner end 10 there is attached the outer end of a connecting strip 26, as by stitching 27. The inner end of each strip 26 is attached to tubular neckband 24 as by stitching 28 at a point spaced inwardly from the inner end of tab 22. Strip 26 is preferably made of elastic material, but may 15 be made of other material having more "give" or "stretch" than neckband 24. If desired, it may be made of the same material as neckband 24 or tab 22, but narrower, so that it will stretch more readily.

With the above construction it will be noted that 20 tabs 22 are not attached directly to neckband 24. The inner ends of tabs 22 are connected by a stretchable strip to the neckband at points spaced inwardly from the inner ends of tabs 22. The lower edges of tabs 22 are connected by stitching 29 to shirt 20, and neckband 24 is 25 also stitched to shirt 20 by stitching 25 which is spaced below stitching 29, as shown in Fig. 2 and mentioned above. The spacing between lines of stitching 25 and 29 permits movement of the lower edge of tabs 22 longitudinally of tubular neckband 24 sufficiently for the desired amount of expansibility of the collar. The sides and upper portions of tabs 22 are entirely free of the sides 24a and 24b of tubular neckband 24, outward motion of the upper portion of tabs 22 being restrained only by the stretchable connecting strips 26. This structure 30 permits a substantial degree of enlargement of the collar band as a whole, that is, of the neckband 24 plus the tabs 22. This enlargement takes place without any stretching of the tubular neckband portions between the point of attachment 28 and the open front ends of neckband 24. Thus, when the neckband expands, there is no stretch of the corresponding top portion 21a of the collar proper 21. Stretching of the top edge of the collar in this region would cause the collar proper to be distorted so that the ends or points of the collar 21 would stand 35 out from the shirt.

An important feature of my invention is the structure by which such objectionable distortion of the collar points is avoided.

Means for detachably connecting tabs 22 together are 40 provided, such as a snap type button 23.

Fig. 4 shows another form of my invention which is constructed in the same manner as described for Figs. 1, 2, and 3, except that in place of using an elastic or stretchable connecting strip 26, a continuous strip 30 extending 45 through tubular neckband 24 connects the tab ends as at 27. This strip 30 may be of elastic or it may be of other suitable material having a sufficient degree of stretch to permit the tabs 22 to be pulled out of the tubular neckband sufficiently to give the combined neckband, that is, comprising band 24 and tabs 22 to expand to the desired degree. If desired, connecting strip 30 may be attached 50 to neckband 24 by suitable stitching at the rear, as indicated at 31.

It will be noted that in both the illustrated embodiments 55 of my invention; i. e., those of Figures 1 and 4, the inner ends of tabs 22 are connected to each other by connecting means which includes at least one member which is more stretchable than tubular neckband 24. In the embodiment of Fig. 1 the said connecting means comprises stretchable connecting strips 26 and the portion of tubular neckband 24 extending around the back of the collar between stitching points 28, 28 on each side. In the em-

bodiment of Fig. 4 the said connecting means comprises stretchable strip 30, which need not be attached to neckband 24 at 31.

My invention provides a collar for a shirt-attached collar which conforms easily and comfortably to the neck. A single size of shirt provided with this type of collar may be used for any of several sizes of conventional shirts. The collar points proper always lie down naturally against the shirt body and are never pulled outwardly by distortion due to stretching of the collar band. By choosing connecting strips such as 26 and 39 of suitable stretchable or elastic material, the collar will conform comfortably and neatly to the neck of the wearer as he moves his head, without any choking or straining. It will also conform neatly to a tie when worn by the individual. The expandable mechanism is completely concealed whether the collar is worn open or closed.

It will be apparent to those skilled in the art that numerous changes within the scope of the appended claims may be made without departing from the spirit of the invention.

I claim:

1. In combination with a shirt, an expandable collar comprising: a tubular neckband attached along its lower portion to said shirt adjacent the top edge thereof, said tubular neckband having spaced apart open front ends at the front of said shirt; a tab in each of said open front ends extending outwardly therefrom, each said tab having an inner end spaced inwardly in said tubular neckband from the respective open front end and being attached along its lower edge from its outer end to a point within said tubular neckband to the top of said shirt; means connecting the inner ends of said tabs, said means including at least one element which is more stretchable than said tubular neckband; means for detachably connecting said tabs together; and a collar member overlying and attached to the top of said tubular neckband; whereby said tabs may be stretched outwardly from said tubular neckband to enlarge said expandable collar as a whole without stretching said collar member.

2. In combination with a shirt, an expandable collar comprising: a neckband attached along its lower edge to said shirt adjacent the top edge thereof, said neckband

having front ends which are spaced apart at the front of said shirt and a tubular portion adjacent each of said front ends, said tubular portions being open at said front ends, a tab in each of said tubular portions, each said tab extending outwardly from the respective front end, having an inner end spaced inwardly from said respective front end, and being attached along its lower edge from its outer end to a point within the respective tubular portion to the top of said shirt; stretchable means for each said tab connecting its inner end to said neckband; and means for connecting said tabs together; whereby each said tab is attached to the top of said shirt, its inner end is connected to said neckband and it has limited freedom to move inwardly and outwardly with respect to the adjacent front end of said neckband.

3. In combination with a shirt, an expandable collar comprising: a tubular neckband attached along its lower edge to said shirt adjacent the top edge thereof, said tubular neckband having open front ends which are spaced apart at the front of said shirt; a tab in each of said open front ends extending outwardly therefrom, each said tab having an inner end in said tubular neckband spaced inwardly from the respective open front end of said tubular neckband and being attached along its lower edge from its outer end to a point within said tubular neckband to the top of said shirt; a connecting strip for each tab, each said strip being attached at its outer end to the inner end of its tab and at its inner end to said neckband inwardly of the inner end of its tab; and means for detachably connecting said tabs together; whereby said tabs have limited freedom to move inwardly and outwardly with respect to said tubular neckband.

4. In combination with a shirt, an expandable collar in accordance with claim 3 wherein said connecting strip for each tab is elastic.
